KNIFE OR OTHER SIMILAR ARTICLE OF FLATWARE

Morris Goodis, West Hempstead, N. Y.

Application April 9, 1954, Serial No. 29,932

Term of patent 3½ years

(Cl. D22—3)

Fig. 1 is a side view of a knife showing my new design, the side opposite thereto being similarly ornamented;

Fig. 2 is an edge view thereof, the opposite edge being similarly unornamented; and

Fig. 3 is a cross-section taken on line 3—3 of Fig. 1.

The essential features of my design reside in the portions shown in solid lines on the drawing.

I claim:

The ornamental design for a knife or other similar article of flatware, substantially as shown and described.
